JUVENILE CRIB

Jens Risom, New York, N. Y., assignor to Colvin Corporation, Long Island City, N. Y., a corporation of New York

Application January 24, 1948, Serial No. 144,013

Term of patent 14 years

(Cl. D5—5)

To all whom it may concern:

Be it known that I, Jens Risom, a citizen of the United States and a resident of the city of New York, county of New York and the State of New York, have invented a new, original, and ornamental Design for a Juvenile Crib, of which the following is the specification, reference being had to the accompanying drawing, forming part thereof.

In the drawing:

The reverse side of this crib is a substantial duplicate of that shown in the drawing, and the opposite end is similar to that shown.

The characteristic features of my design reside in the specific configuration of the end panels.

I claim:

The ornamental design for a juvenile crib, substantially as shown and described.

JENS RISOM.
